(57) **CLAIM**

The ornamental design for a pressurized container with dispensing cap, as shown and described.

DESCRIPTION

FIG. 1 is an isometric view of my new design for a pressurized container with dispensing cap,

FIG. 2 is a front view thereof;

FIG. 3 is a right-side view thereof;

FIG. 4 is a rear view thereof;

FIG. 5 is a top view thereof; and,

FIG. 6 is a bottom view thereof.

1 Claim, 2 Drawing Sheets

FIG. 1

FIG. 5

FIG. 2

FIG. 3

FIG. 4

FIG. 6
